LUTHER C. MCNEAL INVENTOR

BY
Sey & Parsons.
ATTORNEYS.

UNITED STATES PATENT OFFICE.

LUTHER C. MCNEAL, OF ROCHESTER, NEW YORK, ASSIGNOR TO LIBRARY BUREAU OF BOSTON, MASSACHUSETTS, A CORPORATION OF MASSACHUSETTS.

FILE.

SPECIFICATION forming part of Letters Patent No. 689,212, dated December 17, 1901.

Original application filed October 27, 1896, Serial No. 810,192. Divided and this application filed April 3, 1899. Serial No. 711,474. (No model.)

To all whom it may concern:

Be it known that I, LUTHER C. MCNEAL, of Rochester, in the county of Monroe, in the State of New York, (whose post-office address is No. 26 Exchange street, Rochester, New York,) have invented a certain new and useful File, of which the following is a specification.

This application is a division of my application, Serial No. 610,192, filed October 27, 1896.

My invention relates to improvements in files, especially applicable for receiving cards, tickets, checks, notes, and other articles, retaining the same in the desired arrangement, and permitting their removal or rearrangement; and to this end the invention consists, essentially, in the combination, construction, and arrangement of the component parts of a file, as hereinafter fully described, and pointed out in the claims.

In describing this invention reference is had to the accompanying drawings, forming part of this specification, in which like letters indicate corresponding parts in all the views.

Figure 1 is a top plan, partly in section, of my improved file, the movable locking member being shown in its operative position. Fig. 2 is a vertical sectional view taken on line 2 2, Fig. 1. Fig. 3 is a top plan view, partly in section, of a modified construction of my invention.

My improved file consists, essentially, of a frame or card-holder A, a movable locking member B, and means for actuating said locking member. The frame or card-holder A is of any desirable form, size, and construction, and is usually substantially rectangular in cross-section.

The locking member B serves to lock within the frame or card-holder the cards or other articles to be filed therein. This locking member in the form herein shown comprises two bars movable toward each other and from each other, adapted to engage shouldered notches or holding portions of the cards or other articles. This locking member preferably consists of substantially parallel bars b b',

supported by the frame or card-holder A in any desired manner, permitting longitudinal and lateral movement thereof.

In the construction of my invention (illustrated in Figs. 1 and 2) the front ends of said bars are formed with forwardly-diverging portions b² b³, having upturned arms b⁴, and their rear ends are formed with similarly diverging portions b⁵ b⁶, movable in inclined guides or bearings a, provided upon the base of the frame or card-holder. It is obvious, however, that the movable locking member of my file may be supported in any other suitable manner, and in Fig. 3 I have shown a slightly-modified construction of my invention provided with a locking member B¹⁰, consisting of parallel bars b¹⁰ b¹¹, having their opposite ends hinged to the front ends of rearwardly-diverging links b¹², pivoted at their rear ends to the base of the frame or card-holder A¹⁰.

The cards or other articles (not illustrated) to be arranged in my improved file are preferably provided with oppositely-arranged locking-shoulders, formed by apertures extending upwardly from their lower edges and having enlarged upper ends. When said cards or other articles are being arranged in my improved file, the locking member presents a less effective width and readily enters between said locking-shoulders, and when the cards or other articles are suitably arranged the locking member presents a greater effective width and firmly engages said shoulders and locks the cards or articles in position.

My improved file is usually provided with a follower B', which normally holds the cards or other articles in close contact with each other and is movable lengthwise of the locking member B, being generally formed with a lengthwise aperture b⁷ for receiving said locking member. Said follower B' is usually provided with a fastening member B² and an actuating-piece B³. The fastening member B² is hinged at its upper portion to the follower B' and is formed with an aperture b⁸, which receives a rod or bar B⁴, extending

longitudinally beneath the locking member. The actuating-piece B^3 is generally journaled in an upright plane in the follower B' at the rear of the fastening member B^2 and is provided with a lateral shoulder or extension b^9 for rocking the fastening member forwardly and engaging the lower edge of its aperture b^8 with the lower face of the rod or bar B^4 and firmly locking the follower to said rod or bar.

10 The means for actuating the locking member of my improved file preferably consists of a movable operating member C and a spring C' . Said operating member C is here illustrated as consisting of a plunger guided 15 through the front wall of the frame or cardholder A and having its front end provided with a handpiece c and its rear end formed with rearwardly-diverging slots, bearings, or guides c' for receiving the upturned arms b^4 20 of the bars b b' . The spring C' is usually attached to the front wall of the frame or cardholder A and serves to hold the operating member C in its position assumed when the locking member presents its greater effective 25 width. The means for actuating the locking member may, however, be of any other suitable construction, and in Fig. 3 I have shown an actuating means for said locking member consisting of a reciprocating operating member C^{10} , a spring C^{11} , and a catch C^{12} for holding the operating member in its position assumed when the locking member presents its less effective width. Said operating member C^{10} is shown as reciprocally movable 30 through the front wall of the frame or cardholder A and as provided at its front end with an engaging portion and at its rear end with rearwardly-diverging faces constituting guides or bearings engaged with the front 35 ends of the bars b^{10} b^{11} . The spring C^{11} is usually fixed to the base of the frame or cardholder A^{10} , is provided with opposite branches or arms suitably connected to the rear links b^{12} , and serves to normally force the bars b^{10} 40 b^{11} away from each other and cause the locking member to assume its position of greater effective width. The catch C^{12} is generally pivoted to the base of the frame or cardholder A^{10} and is movable into engagement 45 with the operating member C^{10} for preventing movement thereof when the locking member is in its inoperative position.

50 The construction and operation of my improved file will now be readily understood upon reference to the foregoing description and the accompanying drawings, and as it is obvious that the detail construction and arrangement of the component parts of said file may be more or less varied without departing from the spirit of my invention I do not herein limit myself to such exact detail construction and arrangement.

55 As already pointed out, the locking member preferably consists of two bars movable toward each other and from each other, and it will be noted that in the embodiments of my invention herein shown the said two mem-

bers are operated by the wedging action of a longitudinally-movable wedging device, said device being the cam-plate or slotted plunger 70 C in Fig. 1 and the reciprocating member C^{10} in Fig. 3, and in each instance a spring mechanism acts in opposition to the wedging device for holding the locking-bars in one of their two positions, Fig. 1 showing said spring 75 at C' and Fig. 3 showing the spring mechanism at C^{11} . I prefer to have the spring mechanism hold the bars in their expanded position away from each other and depend upon the wedging device for moving the bars toward each other, although, as already stated, I do not limit my invention to the details of construction and operation shown, and it is obvious that other forms of wedging mechanism may be employed, provided the required 85 movement is obtained within the scope of my invention and of certain of the appended claims.

Having thus fully described my invention, what I claim as new, and desire to secure by 90 Letters Patent, is—

1. A card-holder provided with a locking member comprising two longitudinally-movable bars having their ends at one end of the holder divergently bent obliquely to the body 95 of the locking member, guides for said obliquely-bent portions, and means for moving said bars longitudinally.

2. In a card-holder, a locking member comprising two bars movable toward and from 100 each other, and a spring device normally holding said bars spread apart.

3. In a card-holder, a locking member for the cards comprising two bars movable toward and from each other, and inclined bearings 105 for one end of said two bars, one for each bar, and means for moving said inclined bearings longitudinally of said bars for causing the same to expand or contract.

4. In a card-holder, a locking member for 110 the cards comprising two bars movable toward and from each other, and inclined bearings for one end of said two bars, said inclined bearings being provided on the inner end of an operating member projecting through the 115 front of the holder, whereby the movement of said operating member causes the ends of the bars engaging said inclined bearings to move toward or from each other.

5. In a card-holder, a lock-rod comprising 120 a plurality of members movable toward and from each other, said members having portions thereof extending obliquely to the general length of the members, stationary bearings for said oblique portions, and means for 125 moving said members longitudinally.

6. In a card-holder, a lock-rod comprising 130 a plurality of members movable toward and from each other, said members having portions thereof extending obliquely to the general length of the members, stationary bearings for said oblique portions, and a device having at its rear end opposite parts slidingly connected to said members respectively, and

at its forward end means for moving said members longitudinally.

7. In a card-holder, means for locking the cards, comprising two bars movable toward each other and from each other, a longitudinally - movable wedging device for moving said bars into one of said positions, and spring mechanism acting in opposition to said wedging device for holding said bars in the other 10 of said positions.

In testimony whereof I have hereunto signed my name, in the presence of two attesting witnesses, at Rochester, in the county of Monroe, in the State of New York, this 25th day of February, 1899.

LUTHER C. MCNEAL.
